INVENTOR:

Fernando Oscar Jaques, Jr.,
by Chas. H. Luther
ATTORNEY:

UNITED STATES PATENT OFFICE.

FERNANDO OSCAR JAQUES, JR., OF PROVIDENCE, RHODE ISLAND.

EXPANSIBLE TOOTH CROWN.

Application filed May 1, 1926. Serial No. 106,048.

My invention has reference to an improvement in the art of dentistry and more particularly to an improvement in an expansible tooth crown, whereby the method of fitting 5 the crown to a tooth is greatly improved and the time heretofore required for fitting the crown to the tooth, reduced to a minimum.

In fitting metal tooth crowns to teeth, it is necessary for the crown to have a perfect 10 fit on the tooth. As heretofore done, it required a large number of fittings, to obtain an exact fit of the crown on the tooth.

The object of my invention is to improve the construction of a tooth crown 15 whereby the number of fittings and time heretofore required to fit a crown to a tooth, are reduced to a minimum.

My invention consists in the peculiar and novel construction of an expansible tooth 20 crown, said expansible tooth crown having details of construction, as will be more fully set forth hereinafter and claimed.

Figure 1 is a vertical view of my improved expansible tooth crown for a right 25 upper first bicuspid tooth, looking at the mesial surface of the crown.

Figure 2 is a vertical view of the same 30 expansible tooth crown, looking at the buccal surface of the crown.

Figure 3 is a neck view looking down 35 on the upper open end of the crown.

Figure 4 is a closed end view of the crown looking at the occlusal surface of the crown, and

Figure 5 is an open end neck view of the 40 crown, similar to Figure 3 and showing the crown expanded a predetermined amount.

In the drawing 6 indicates my improved 45 expansible tooth crown constructed to have an open neck end 7, a mesial surface 8 and an occlusal surface 9. The crown shown is for a right upper first bicuspid tooth. The crown 6 is split at 10 lengthwise of the crown preferably through the mesial surface 45 8 or that part of the crown and then split over into the center of the occlusal surface 9 or that part of the crown. This split is made through the thickness of the crown or shell, at an angle from the outside 50 in, and forms an outer free edge 11, which laps over the outside mesial surface 8 of the crown and an inner free edge 12 which laps over the inner surface of the crown, as shown in Figures 1, 3 and 5.

When in use, the tooth to be crowned is 55 first prepared in the usual way for the crown. My improved expansible tooth crown, preferably of gold, is then placed over the tooth. If the tooth is large the crown will expand over the tooth and if the tooth is small, the crown is contracted onto the tooth. When the crown is exactly fitted to the tooth, a line is marked on the mesial surface 8 of the crown down the edge 11, of the outer overlapping part of the crown. 60 The crown is now removed from the tooth. If the overlapping parts of the crown become misplaced in removing the crown from the tooth, the edge 11 is moved to coincide with the marked line on the mesial surface 65 8 of the crown and the overlapping parts of the crown secured together by solder or other means. The crown, now a perfect fit for the tooth is again placed onto the tooth and cemented to the tooth. 70

By the use of my improved expansible tooth crowns, the heretofore large numbers of fittings required to fit a crown to a tooth are reduced to a minimum and the large amount of work heretofore necessary on a 80 tooth to be crowned, is also reduced.

Having thus described my invention I claim as new:

1. An expansible tooth crown having a split formed at an angle through the crown, 45 said split forming a free edge overlapping the outside of the crown and a free edge overlapping the inside of the crown, the split extending into the occlusal surface of the crown, all formed integral, for the purpose 90 as described.

2. An expansible tooth crown having a split through the mesial and occlusal parts of the crown, said split being at an angle through the crown and forming overlapping 95 members on the crown, one overlapping member having an edge on the outside of the crown and the other overlapping member having an edge on the inside of the crown, the split extending lengthwise of the 100 crown and then over and into the center of the occlusal surface of the crown, all formed integral, for the purpose as described.

In testimony whereof, I have signed my 105 name to this specification.

FERNANDO OSCAR JAQUES, JR.
